(57) **CLAIM**

The ornamental design for an automobile tire, as shown and
described.

DESCRIPTION

FIG. 1 is a perspective view of an automobile tire of our
design, which is also shown in FIGS. 2-7;

FIG. 2 is a front view;

FIG. 3 is a rear view;

FIG. 4 is a side view;

FIG. 5 is a top view;

FIG. 6 is an enlarged fragmentary view of the tire of FIG. 2;
and,

FIG. 7 is an enlarged fragmentary cross-sectional view
thereof, taken in the direction of line 7—7 of FIG. 6.
